UNITED STATES PATENT OFFICE.

SEABORN JONES SPEIR, OF AUSTIN, TEXAS, ASSIGNOR OF ONE-HALF TO FERDINAND W. MENKING, OF FAYETTEVILLE, TEXAS.

WIRE CLAMP AND INSULATOR HOLDER.

Application filed July 2, 1927. Serial No. 203,232.

This invention relates to electrical conductor holders and its general object is to provide a combined clamp and insulator holder for conductors that not only threadedly receives an insulator but includes means for securely clamping the same thereon, with the result the insulator cannot work loose under strain or movement of the conductor which is also clamped to the insulator by a portion of my device.

Another object of the invention is to provide a conductor clamp and insulator holder, that is capable of being secured to a cross bar of a pole, in an easy and expeditious manner and so that casual disarrangement or displacement thereof is practically impossible.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side elevation of my invention and shows the same in applied position to a cross bar of a pole and receiving a conductor wire.

Figure 2 is a top plan view thereof.

Figure 3 is a sectional view taken on line 3-3 of Figure 1.

Figure 4 is a longitudinal sectional view taken through the device.

Figure 5 is a perspective view showing the position assumed by the clamping means before it is applied to a conductor.

Figure 6 is a top plan view of the insulator holder per se.

Figure 7 illustrates the application of slightly modified forms of the device to the cross arms of a pole.

Figure 8 is a rear elevation of one of the modified forms as shown in Figure 7 and which is adapted to replace the wooden pipe holders as suggested therein.

Referring to the drawings in detail, the letter A indicates a fragmentary portion of a cross bar of a pole and to which is secured the insulator holder which includes a flat elongated body strip 1 provided with spaced parallel openings 2 to receive securing bolts

3 as clearly shown in Figures 1 and 2 of the drawings. Integrally formed with one end of the body strip 1 is a curved arm 4 which terminates in parallelism with and above the plane of the body strip 1 and formed on said arm 4 is a threaded shank 5 arranged to overlie the body strip as best shown in Figure 4. The shank 5 is tapered in the usual manner and is adapted to receive an insulator B of the usual construction. Formed integral with the shank and at its juncture with the arm 4 is a substantially V-shaped projection 6 which extends rearwardly and upwardly from the shank in a manner to provide a recess 7 for a purpose which will be presently apparent.

The insulator B is threadedly secured to the shank 5 in the usual manner, and in order to prevent casual displacement of the insulator B, and to fix a conductor thereto, I have provided a substantially bail shape member formed from wire and includes parallel arms 8 adapted to extend longitudinally of the insulator upon diametrically opposite sides thereof as best shown in Figure 2 and these arms 8 have formed on one end converging portions 9 which terminate into a straight part 10 to provide a bearing for receiving a spool 11 having a concaved outer surface so as to be snugly accommodated in the recess 7 as best shown in Figure 2 of the drawings. The arms 8 have their free ends bent outwardly at right angles upon themselves to provide conductor receiving portions 12, while fixed to the arms 8 adjacent their juncture with the portions 12 is a substantially U-shaped wire member 13 adapted to be received in the circumferential groove C of the insulator B, and the conductor which is indicated by the letter D is curved so as to be received in the remaining portion of the groove C and is held therein by winding the portions 12 thereabout as best shown in Figure 2.

It will be obvious from the above that I have provided a combined clamp and insulator holder that performs a dual function for securing the insulator B to the holder, as the insulator B is threadedly secured to the shank 5 and is further held in operative position thereon through the instrumentality of the bail which includes the arms 8 and the engagement of the spool 11 with its recess 7 as best shown in Figure 4 of the drawings. Again, the insulator holder is secured

to the bar A in a manner whereby lateral strain or constant movement of the conductor will not displace the same nor will the insulator B be displaced by such strain or movement. While I have shown my insulator holder fixed to a cross bar A of a pole, I want it understood that it can be associated with any type of supporting means secured to a pole or otherwise, and it can be secured directly to the pole or any other place where a device of this character is needed.

In Figure 7 I have illustrated the application of my holder in other forms to the cross arms of a pole, and it will be noted that a plurality of holders of the form just described are formed in parallelism with a single strip 14 which is to be secured to the cross arms by bolts 15 as shown. The upper cross arm in Figure 7 is arranged at an inclination and secured to the pole accordingly, so as to be properly braced, due to the fact that the conductors that are adapted to be secured to the holders of this cross arm are to make a turn from their securing point, in an opposed direction to the angle of inclination of the cross arm.

For repairing old lines, I provide a strip holder as best shown in Figure 8 and this holder includes the curved arm 4, and the threaded shank 5 for receiving the insulator B which is secured thereto by the same means and in the same manner as in the other forms, but it will be noted that the arm 5 has formed therewith and depending therefrom a U-shaped strap 17 with aligned openings in its arms to receive a bolt and nut connection 18 for securing the holder to the lower cross bar as shown in Figure 7.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device of the character described comprising a curved arm, means for securing said arm to a supporting means, a threaded shank formed with said arm, a projection extending from said shank and providing a recess at the juncture thereof with said arm, an insulator threaded on said shank and having a circumferential groove therein, means arranged in said groove and extending rearwardly of said insulator, means secured to the rearward portion of said means and received in said recess to cooperate with the first mentioned means to prevent longitudinal movement of said insulator, and means for securing a conductor to said first mentioned means and in said groove.

2. An insulator holder and wire clamp of

the character described comprising an arm, means for securing said arm to a cross arm of a pole, a tapered shank formed with the free end of said arm and being threaded, an insulator having a circumferential groove formed therein and adapted to be secured on said shank, a projection extending from said shank and forming a recess at the juncture of said shank with said arm, means securing a conductor to said insulator, and a spool secured to said means and being arranged in the recess to prevent longitudinal movement of said insulator on said shank.

3. An insulator holder and wire clamp of the character described comprising a body strip adapted to be secured to a supporting means, a curved arm extending from adjacent one end thereof, a tapered shank formed with said arm and arranged in parallelism with said body strip, a threaded insulator having a circumferential groove formed therein and being threaded on said shank, a projection formed with said shank and extending rearwardly therefrom in a manner to provide a recess at the juncture of the arm with said shank, means for securing a conductor to the insulator and the insulator to the shank and including a pair of parallel arms, converging portions formed on said arms, a bearing formed with said converging portion, a spool on said bearing and being arranged in said recess, right angle portions formed with said arms and being wrapped around said conductor for holding the same in said groove, and a substantially U-shaped member secured to said arms and being arranged in said groove.

4. An insulator holder and clamp of the character described comprising a flat body strip adapted to be secured to a support, arms formed on one strip and rising therefrom, a tapered shank for each arm and arranged in parallelism with said strip, an insulator having a circumferential groove formed therein and being threaded on said shank, a projection extending outwardly from said shank and forming a recess at the juncture of the shank with the arm, and means to prevent longitudinal movement of said insulator and including a pair of arms, converging portions formed with the pair of arms and terminating in a straight portion providing a bearing, means mounted on said bearing and received in said recess to prevent longitudinal movement of said insulator on said shank, a substantially U-shaped member secured to said pair of arms and arranged in said groove, and right angle portions formed with said pair of arms and adapted for securing a conductor in said groove.

5. An insulator holder and conductor clamp comprising a body strip provided with spaced parallel openings, means adapted to be arranged in said openings for se-

curing said strip to a support, a curved arm formed with said strip and extending from adjacent one end thereof, a threaded tapered shank formed with the free end of said arm, an insulator having a circumferential groove formed therein and being threadedly received by said shank, a projection extending outwardly from the large end of said shank and forming a groove at the juncture ¹⁰ of the arm with the shank, means to pre-

vent longitudinal movement of said insulator on its shank and including means arranged in said groove and recess respectively, and means formed with said first mentioned means for securing a conductor in ¹⁵ said groove.

In testimony whereof, I affix my signature.

S. J. SPEIR.
